UNITED STATES PATENT OFFICE.

SYLVESTER L. HILL, OF BOSTON, MASSACHUSETTS.

TRANSOM-LIFTER.

SPECIFICATION forming part of Letters Patent No. 376,955, dated January 24, 1888.

Application filed March 26, 1887. Serial No. 232,581. (No model.)

To all whom it may concern:

Be it known that I, SYLVESTER L. HILL, of the city of Boston, in the county of Suffolk and State of Massachusetts, have invented certain new and useful Improvements in Skylight-Lifters, of which the following is a full, clear, and exact description.

The invention relates to devices for raising and lowering skylights, scuttles, &c., in which the skylight is attached to a bar which is caused to slide up and down in a suitable sleeve or guide affixed to the casing; and it consists, first, in the improved form of the bar and of the sleeve or guide in which it slides; second, in the spring-pawl engaging with notches in the bar, whereby the said bar is secured in position when the skylight has been raised to the desired point; third, in a roller-guide for the operating-rope.

In the drawings forming part of this specification, Figure 1 is an elevation of the improved lifter as attached to the skylight. Fig. 2 is a perspective view showing the same in detail. Fig. 3 is a front elevation of a portion of the same, showing the spring-pawl locking device.

In the drawings, A is the skylight, and B the casing to which it is hinged. To the casing B is secured a bracket, C, provided with lugs c c. The sleeve or guide D is attached to the bracket C by the pin c', which passes through holes in the lugs c c of the bracket C. The guide D can therefore rotate around the pin c', to allow of the changes in direction of the bar E due to the rise and fall of the skylight. The guide D consists of a flat frame or back, d, provided with a short sleeve, d', at its upper extremity and a similar sleeve, d'', at its lower extremity, through both of which passes the bar E. It also has a pulley, P, adapted to carry a rope, R, and inclosed in a suitable box, p. The lug L is pierced to receive the end of the rope R. The lugs L' L'' are bored to receive the pin l, carrying the roller l', and serve as a guide to the rope R. The frame or back d, sleeves d' and d'', pulley-box p, and lugs L, L', and L'' are cast in one piece. The bar E is rectangular in section

and of greater width than thickness. It is attached to the skylight by a bracket, C', having a bent staple passing through a hole in its extremity. It is adapted to fit loosely and slide in the sleeves d' d'' of the guide D. At its lower extremity it has a pulley, P', inclosed in a suitable box, p. The spring-pawl G rotates upon the pin g, by which it is attached to the frame d, and its nose g' is caused to engage with the notches g' g' of the bar E by its spring g''. It is provided with a release-cord, R'. The rope R, by which the bar E is raised and lowered, is attached at one end to the lug L. It thence passes successively around the pulleys P' and P and through the guide L' L''.

In order to raise or lower the bar E, the pawl G must be first disengaged by the release-cord R'.

I preferably make the bracket C, the guide D, and pulleys P and P' of metal and the bar E of spring-steel.

Having thus described my invention, what I claim, and desire to secure by Letters Patent, is—

1. A lifter for transoms, skylights, &c., consisting of a flat and notched lifting-bar, E, pivotally connected to the sash, a swinging guide, D, having sleeves d' d'', and a pawl, G, having spring g'', to engage the notches of said bar E, in combination with the sheave-wheels P P' and an operating-cord, R, substantially as described, for the purposes specified.

2. A lifter for transoms, skylights, &c., consisting of a flat and notched lifting-bar, E, pivotally connected to the sash, a swinging guide, D, having pawl G and its spring g'', sleeves d' d'', and lugs L' L'', carrying roller l', in combination with the sheave-wheels P P' and an operating-cord, R, substantially as described, for the purposes specified.

In testimony whereof I have hereunto set my hand in the presence of two subscribing witnesses.

SYLVESTER L. HILL.
